GRINDING MACHINE

Harold L. Blood, Worcester, Mass., assignor to
The Heald Machine Company, Worcester,
Mass., a corporation of Massachusetts

Application January 13, 1937, Serial No. 120,419

10 Claims. (Cl. 51—95)

The present invention relates to grinding machines and particularly to a machine in which the rate of crossfeed movement between the grinding wheel and the workpiece is reduced upon engagement between the wheel and the work with the crossfeed movement occurring rapidly until this engagement takes place.

In practically all types of grinding machines, but more especially internal grinding machines, the workpiece and grinding wheel at the beginning of the grinding operation are spaced transversely of the machine relative to each other so that a transverse movement of either the wheel or the work-piece is necessary to bring the wheel and workpiece into grinding contact. Until the wheel and workpiece are in engagement no grinding occurs and the relative movement transversely of the machine must accordingly take place at a rapid rate in order to reduce the inoperative time of each grinding operation. One of the principal objects of the present invention is to provide for a reduction in the rate of cross-feed movement immediately upon engagement between the grinding wheel and the workpiece with this reduction occurring independently of the unfinished size of the workpiece.

In a copending application filed by Schmidt and Blood, Serial No. 68,291, filed March 11, 1936, is disclosed a structure by which the rate of cross-feed movement may be reduced upon engagement between the wheel and the workpiece and this structure incorporates an electrical circuit by which the grinding instrumentalities are controlled. This arrangement is entirely satisfactory in operation, but it is desirable at times, and in certain types of machines, to avoid the electrical circuits and connections. One of the objects of the present invention is to provide a mechanically actuated structure for reducing the rate of cross-feed movement or for procuring other changes in the grinding operation upon engagement between the wheel and the workpiece.

The present invention accordingly incorporates an alternative mechanism for accomplishing the same, or a similar result, as in the Schmidt and Blood application. In the present invention the change in the grinding operation which is procured by engagement between the wheel and the workpiece is effected by a slight movement of the wheelhead relative to the base of the machine, and mechanical elements provide a connection between the wheelhead and the mechanism controlled thereby.

Other and further objects and advantages of the invention will more fully appear from the fol-

lowing detailed description taken in connection with the accompanying drawings in which—

Fig. 1 is a front elevation of a machine embodying the invention.

Fig. 2 is a plan view of the machine of Fig. 1. 5

Fig. 3 is a vertical section substantially along the line 3—3 of Fig. 2.

Fig. 4 is a vertical section substantially along the line 4—4 of Fig. 3, with parts broken away to show the crossfeed mechanism more clearly. 10

Fig. 5 is an end elevation, with parts broken away, of the wheelhead and associated mechanism.

Fig. 6 is a fluid pressure diagram.

Fig. 7 is a view corresponding to Fig. 5 showing a modification.

Like reference characters refer to like parts in the different figures.

Referring first to Fig. 1, the machine has the usual reciprocating table 1 provided in an internal grinding machine; either the grinding wheel or the workpiece to be ground is carried on said table, the reciprocations of the latter operating in either case to produce a relative translatory movement between the wheel and the workpiece. 20 In the construction shown, the table supports and carries a workhead 2 and the wheelhead 3 is mounted on a bridge 4 which spans the guideways 5, Fig. 3, provided by the base 6 of the machine for the movements of the table 1. The 30 grinding wheel 1 is carried on a spindle 8 journaled in the wheelhead 3, and is suitably rotated at a high rate of speed by any well known mechanism, which, in the present instance, consists of a motor, not shown, in the base of the 35 machine, connected by a belt, also not shown, to a pulley 9, Fig. 5, on the spindle.

The workpiece 6, Figs. 1 and 2, is mounted in a suitable work-supporting structure which may be in the form of a chuck 10 carried on a spindle 11 journaled in the workhead. The chuck is preferably driven at a relatively slow rate of speed from a motor 12 connected to the spindle 11 by a belt 13. The clutch mechanism 14, of any well known construction, provides for stopping 40 the rotation of the chuck without interfering with the operation of the motor 12. The clutch mechanism is under the control of a handle 15 easily accessible to the operator of the machine.

The reciprocations of the table 1 to cause the 50 desired relative traverse between the rotating grinding wheel and the work-supporting structure are imparted in any well known manner, as by the use of fluid pressure controlling and reversing mechanism, one type of which is de- 55

scribed in the Blood and Burns Patent No. 2,011,-
705, dated August 20, 1935. It is sufficient to
note for the purpose of the present application
that reversal of the table is procured at each end
5 of the normal working stroke by spaced reversing
dogs 16 and 17, which are carried by blocks 18
and 19 adjustably mounted on the front of the
table 1 and adapted alternately to engage and
move a reversing lever 20. The reversing lever
10 is connected by suitable mechanism to a reversing
valve 21, Fig. 6. The reversing lever 20 during
the grinding operation, when the grinding wheel
is within the bore of the workpiece, is so located
is to be engaged alternately by the reversing
15 dogs.

Referring now to Fig. 6, the pump 22, driven
by a motor 23, directs fluid under pressure from a
tank 24 through a pipe 25 to a casing 26 in which
the reversing valve 21 is positioned. The casing
20 26 has an inlet port 27 to which the pipe 25 is
connected, and also has spaced outlet ports 28
and 29 connected by pipes 30 and 31, respectively,
to the left and right hand ends of a cylinder
25 32 mounted in the base of the machine. A
piston 33, slidable in the cylinder, has a piston
rod 34 connected to a depending lug 35 on the
table 1. The reversing valve alternately directs
fluid under pressure from the inlet port 27 to the
outlet ports 28 and 29 and, at the same time, con-
30 nects the opposite outlet port to an exhaust port
36 suitably connected to the tank.

The crossfeed movement between the work-
piece and the grinding wheel is obtained by
transverse movement of the wheelhead 3 on the
35 bridge 4. Movement of the cross-slide 37, Fig. 3,
on which the wheelhead is mounted, is effected
by rotation of the crossfeed screw 38, which is
held against endwise movement by anti-friction
30 bearings 39 engageable with the rearward end
40 thereof. The crossfeed screw engages an inter-
nally threaded portion 40 of the cross-slide for
effecting the transverse movement thereof. On
the forward end of the crossfeed screw 38 is
mounted a gear 41 which meshes with a pinion
45 42 secured against turning movement on a shaft
43 journaled in a housing 44 for the crossfeed
mechanism. Also secured to the shaft 43 in
spaced relation to the gear 42 is a ratchet wheel
45 engageable by spaced oppositely directed pawls
46 and 47, Fig. 4, carried by an annular member
48 secured against turning movement on a sleeve
49 journaled on the shaft 43. The sleeve 49
55 has an integral pinion 50 engageable by a rack
51 horizontally slidable in the casing 44, said
rack being held in engagement with the pinion
by a bearing 52. The rack 51 is shifted by a fluid
pressure mechanism, hereinafter described in de-
tail, and procures through the pawl and ratchet
50 arrangement a rotation of the shaft 43, and ac-
cordingly a rotation of the crossfeed screw.
Manual rotation of the crossfeed screw is by a
hand wheel 43' on the end of the shaft 43.

The pawl and ratchet arrangement is fully
described in the Guild Patent No. 1,971,138, dated
65 August 21, 1934. It is sufficient to note for the
purpose of the present application that this
double pawl arrangement permits, during the
return of the crossfeed slide to original position,
in readiness for a subsequent grinding operation,
70 a compensation for the reduction in size of the
grinding wheel as a result of wear and the dress-
ing operation performed thereon during the pre-
ceding grinding operation. With reference again
75 to Figs. 3 and 4, it will be noted that both of the
pawls are normally held in operative engagement

with the ratchet by a spring 53, so that a rotation
of the annular member 48 provides a correspond-
ing rotation of the ratchet 45. The pawl 47 is
operative during the crossfeed movement, and
the pawl 46 is operative during the retraction of
the crossfeed movement, the latter involving a
5 counterclockwise rotation of the member 48. The
pawl 46 is rendered inoperative during a part
of the movement of the annular member 48 in
the counterclockwise direction, so that the cross-
slide is retracted a slightly shorter distance than
10 it is moved forward during the crossfeed move-
ment.

To effect this compensatory movement, the
shaft 43 has journalled thereon an arm 54 having
15 a gear segment 55 on the outer end thereof. The
gear segment engages with a pinion 56 on a shaft
57 journalled in the front wall of the housing
44. The outer end of the shaft 57 has a knurled
knob 58 by which said shaft is turned for shift-
20 ing the position of the arm 54. Integral with the
arm 54 is a cam 59 in a position for engagement
with a pin 60 on the pawl 46 just before the ter-
mination of the crossfeed movement. Thus dur-
ing the first part of the retraction of the cross-
25 feed movement, the pawl 46 is inoperative and a
rotation of the annular member 48 procures no
corresponding movement of the ratchet wheel un-
til the pawl 46 is released by the cam 59. Dur-
ing the remainder of the counterclockwise move-
30 ment of the member 48, the retraction of the
crossfeed movement takes place.

Referring now to Figs. 4 and 6, the rack 51 is
carried on the end of a piston rod 51, extending
from a piston 62 slidable in a horizontally posi-
35 tioned cylinder 63 mounted on the front of the
bridge. Fluid under pressure is directed alter-
nately to opposite ends of the cylinder 63, for
procuring a crossfeed movement and the retrac-
tion thereof. As shown in Fig. 6, fluid under
40 pressure from the pipe 25 passes through a pipe
64 to the inlet port 65 of a reversing valve casing
66 for a reversing valve 67 for the crossfeed
mechanism. An outlet port 68 in the casing 66
is connected by a conduit 69 to the left hand end
45 of the cylinder 63 and a port 70 is connected by
a pipe 71 through suitable valve mechanisms,
hereinafter described, to the right hand end of
the cylinder. An exhaust port 72 for the revers-
ing valve casing provides for exhaust of fluid
50 from the cylinder and this port is suitably con-
nected to the tank 24.

The structure above described is similar to
structure already disclosed and claimed in prior
55 patents and pending applications and is not of it-
self the present invention. The latter involves
the attainment in connection with the above or
similar grinding machine elements of the objects
and novel features above set forth. In accordance
60 with the present invention the movement of the
wheelhead by reason of engagement between the
wheel and the workpiece is used to procure, by
mechanical elements, a change in the grinding
operation. This change, in the present instance,
65 although it will be apparent that other changes
in the grinding operation may be controlled by
similar mechanism.

With reference now to Figs. 5 and 6, the wheel-
head 3 is supported for rocking movement on the
70 cross-slide 37 by means of flat springs 73 attached
at their opposite ends by bolts 74 to a slide 75
secured in the cross-slide. The springs 73 are
centrally connected by suitable bolts 76 to the
wheelhead and the springs are shaped to provide
75

for a small amount of oscillatory movement of the wheelhead on the slide 75, the wheelhead rocking about the lugs 75' in line with the bolts 76.

Referring again to Fig. 5, the cross-slide 37 has mounted thereon, forwardly of the wheelhead, a housing 77 on which is mounted for rocking movement a lever 78. The support for this lever preferably comprises one or more flat springs 79 connected at one end to the housing 77 and at the opposite end to the lever between the ends thereof. One end of the lever 78 is connected by similar flat springs 80 to the wheelhead, and it will be apparent that rocking movement of the wheelhead in the direction indicated by the arrow 81 will procure a counterclockwise turning movement of the lever 78. The rocking movement of the wheelhead is limited by an adjustable bolt 82 in the housing 77. The housing 77 has a recess therein to form a casing for a valve 83, the projecting end of which is engaged by the lower end of the lever 78 for shifting of the valve in response to rocking movement of the lever.

With reference to Fig. 6, the housing or valve casing 77 has a port 84 connected to the pipe 71 and a second port 85 in the housing and axially spaced from the port 84 is also connected to the pipe 71 by a conduit 86. A port 87 in the housing 77 is connected by a conduit 88, in which is located a main throttle valve 89, to the right hand end of the cylinder 63. The housing 77 also has an exhaust port 90 suitably connected to the tank 24.

With the valve 83 in the position shown, which is the position of the valve at the beginning of the grinding operation, a reduced portion 91 of the valve provides a fluid connection between the ports 84 and 87 for directing fluid under pressure to the right hand end of the cylinder 63 when the valve 67 is shifted at the beginning of the grinding operation. When the grinding wheel engages the workpiece, the wheelhead 3 is rocked counterclockwise against the screw 82 and the valve 83 is thus shifted to the right, closing the port 84 and uncovering the port 85 to allow fluid under pressure from this port to enter an axial channel 92, communicating with a reduced portion 93 in said valve, for directing fluid under pressure to the left hand end of said valve, thereby urging it into its extreme right hand position where it remains during the remainder of the grinding operation. With the valve 83 urged to the right by fluid under pressure, the valve holds the wheelhead 3 rigidly against the stop screw 82 during the entire operative part of the grinding operation.

After the flow of fluid under pressure past the valve 83 and into the right hand end of the cylinder 63 is cut off, as above described, fluid under pressure still enters the right hand end of the cylinder 63 for continuing the crossfeed movement at a much slower rate. Referring again to Fig. 6, the pipe 71 is connected by a conduit 94 to a channel 95 in a block 96 in which is positioned the casing 97 of a valve 98. The block 96 is secured to the bridge 4 and to the cylinder 63. The channel 95 intersects spaced bores in said block in which are located throttle valves 99 and 100, the former controlling the rate of crossfeed movement during the rough grinding operation and the latter controlling the rate of crossfeed movement during the finish operation. The valve casing 97 has a port 101 communicating with the throttle valve 99, and the valve 98 has a reduced portion 102 which provides a connection

between the end of the valve 99 and a channel 103 in the casing communicating with a channel 104 in the cylinder 63, the latter channel connecting with the right hand end of the cylinder 63 so that after the valve 83 is shifted, the crossfeed movement continues under the control of the valve 99. It will be apparent that fluid under pressure enters the cylinder 63 through the rough feed valve 99 during the rapid crossfeed movement of the wheel into engagement with the workpiece, but the small amount of fluid passing through the valve 99 does not affect the functions of the valve 83.

As the grinding operation continues, the control valve 98 is shifted to the right by a cam 105, Fig. 4, carried by the annular member 48. This cam engages a roller 106 on a plunger 107 slideable in a cap 108 secured to the block 96 in line with the valve 98. When the valve 98 is shifted by the cam 105, the flow of fluid through the valve 99 is cut off and fluid then passes from the fine feed valve 100 through a port 109, Fig. 6, in the casing 97, around a reduced portion 110 of the valve 98 and into the channel 103 so that during the last part of the grinding operation the crossfeed movement occurs at a very slow rate as determined by the fine feed valve 100. A coil spring 111 at the right hand end of the valve 98 normally urges the valve to the left against the plunger 107, movement of the latter to the left being limited by a ring 112; Fig. 4, on the cap 108.

The grinding operation may be brought to a close by any suitable mechanism, as for example, the mechanism fully disclosed in the Blood and Burns Patent No. 2,011,705, dated August 20, 1935. Whatever the type of size-controlling mechanism used, the grinding wheel and workpiece are axially separated at the completion of the grinding operation by rendering inoperative the reversing dog 17. Simultaneously, the valve 67 is shifted by suitable mechanism, not shown, for directing fluid under pressure to the left hand end of the cylinder 63 for a retraction of the crossfeed movement. At this time the fluid in the right hand end of the cylinder 63 exhausts through pipe 88 and the port 84 into the pipe 71. This is possible since, immediately upon shifting of the valve 67, the fluid under pressure at the left hand end of the valve 83 is allowed to exhaust through either port 86 or 90, and the valve 83 is returned to the original position of Figs. 5 and 6 by reason of the resilient mounting of the wheelhead.

The operation of the machine so far as it is applicable to the present invention will be briefly summarized. With the machine in the position of Fig. 1, and with a workpiece *a* positioned in the chuck 10, the handle 15 is manually shifted to cause rotation of the workpiece. Movement of the table to the right to bring the workpiece and grinding wheel into operative position is then procured by movement of the lever 113, Fig. 1, which is suitably connected to the table reversing valve 21. As the table reaches operative grinding position, the valve 67 is shifted by any suitable mechanism, but preferably in response to the table movement, to direct fluid under pressure into the right hand end of the cylinder 63 for the crossfeed movement.

At the beginning of the crossfeed movement, the valves 83 and 98 are in the position shown and the rate of crossfeed movement is under the control of the main throttle valve 89, for a lateral or crossfeed movement of the grinding wheel

- relative to the workpiece from the position of Fig. 3 into engagement with the bore of the workpiece. When the grinding wheel engages the workpiece, the pressure exerted by the wheel against the workpiece causes counterclockwise movement of the wheelhead on the cross-slide, thereby shifting the valve 83 to the right for locking the wheelhead against oscillatory movement by directing fluid under pressure to the 10 left hand end of the valve 83. The shifting of the valve 83 also procures a reduction in the rate of crossfeed movement by cutting off the flow of fluid under pressure through said valve to the cylinder 63.
- 15 After the reduction in the rate of crossfeed movement by movement of the valve 83, the grinding operation continues in the usual manner until the grinding operation is brought to a close by an extended movement of the table to 20 the left. At the end of the grinding operation, the valve 67 is shifted, as above pointed out, to provide for a retraction of the crossfeed movement which at the same time allows the valve 83 to return to its original position with a resultant 25 return of the wheelhead to its original position in readiness for a subsequent grinding operation.

It will be understood that, although the wheelhead is shown to be the oscillatory member by which the change in the grinding operation is 30 procured, in certain instances the workhead may, if desirable, be mounted for oscillation instead of the wheelhead with the structure now shown on the wheelhead mounted for actuation by the workhead.

35 With reference now to Fig. 7, in which is shown a modification, the wheelhead 3' has a projecting arm 114 directly connected to the projecting end of the valve 83' corresponding to the valve 83. The valve is located in a casing forming 40 part of a housing 77' and the latter has an adjustable bolt 82' to limit the oscillatory movement of the wheelhead by engagement with a projecting lug 150 on the wheelhead. The valve 83' has the reduced portion 91' which provides 45 a connection between the ports 84' and 87' and in the housing 77', and the latter also has the port 85' and exhaust port 98'. An axial channel 92' corresponds to the axial channel 92 and communicates with the reduced portion 93'. The 50 operation of this modification is similar to that above outlined since upon engagement between the grinding wheel and the workpiece during the crossfeed movement the wheelhead 3' is rocked counterclockwise, shifting the valve 83' upwardly. This movement of the valve 83' corresponds 55 to a movement of the valve 83 to the right. The remainder of the operation is precisely the same as above outlined.

From the foregoing it will be apparent that 60 the invention provides a mechanism for procuring a change in the grinding operation by engagement between the grinding wheel and the workpiece. The mechanism is mechanically actuated to avoid the use of any electrical connections where they are not desirable. One change 65 in the grinding operation may be, as above disclosed, a reduction in the rate of crossfeed movement, and this is procured by a movement of the wheelhead relative to the base, resulting from 70 engagement between the wheel and the workpiece. This movement of the wheelhead will take place independently of variations in the unfinished diameters of successive workpieces and the device is accordingly operative for the successive grinding of a plurality of workpieces 75

which vary substantially in unfinished diameter.

I claim:—

1. In a grinding machine, a wheel supporting member having a wheel thereon, a work-supporting member having a workpiece mounted therein, means for procuring a relative movement between said members to bring the wheel and workpiece into engagement, means responsive to engagement between the wheel and the workpiece for procuring a movement of one of said members relative to the supporting structure therefor, means responsive to said last movement for procuring a change in the grinding operation, and hydraulically actuated means for preventing further movement of said movable member relative to the supporting structure after the wheel and workpiece are in engagement. 15

2. In a grinding machine, a wheel supporting member having a wheel thereon, a work-supporting member having a workpiece mounted therein, means for procuring a relative movement between said members to bring the wheel and workpiece into engagement, means responsive to engagement between the wheel and the workpiece for procuring a movement of one of said members relative to the supporting structure therefor, means responsive to said last movement for procuring a change in the grinding operation, and hydraulically actuated means for preventing further movement of said movable member relative to the supporting structure during the remainder of the grinding operation. 20

3. In a grinding machine, a wheel supporting member having a wheel thereon, a work-supporting member having a workpiece mounted therein, means for procuring a relative movement between said members to bring the wheel and workpiece into engagement, means responsive to engagement between the wheel and the workpiece for procuring a movement of one of said members relative to the supporting structure therefor, and hydraulically actuated means rendered operative by said last movement for locking the movable member against further movement relative to the supporting structure during the remainder of the grinding operation. 25

4. In a grinding machine, a wheel supporting member having a wheel thereon, a work-supporting member having a workpiece mounted therein, means for procuring a relative movement between said members to bring the wheel and workpiece into engagement, means responsive to engagement between the wheel and the workpiece for procuring a movement of one of said members relative to the supporting structure therefor, means responsive to said last movement for reducing the rate of said relative movement, and fluid pressure means for locking the movable member against further movement relative to the supporting structure during the remainder of the grinding operation. 30

5. In a grinding machine, a wheel supporting member having a wheel thereon, a work-supporting member having a workpiece mounted therein, hydraulically actuated means for procuring a relative movement between said members, a valve for controlling the admission of fluid to said hydraulically actuated means, means responsive to engagement between the wheel and the workpiece for procuring a movement of one of said members relative to the supporting structure therefor, and means responsive to said last movement for shifting said valve directly in response to said last movement. 35

6. In a grinding machine, a wheel supporting member having a wheel thereon, a work-supporting member having a workpiece mounted therein, hydraulically actuated means for procuring a relative movement between said members, a valve for controlling the admission of fluid to said hydraulically actuated means, means responsive to engagement between the wheel and the workpiece for procuring a movement of one of said members relative to the supporting structure therefor, means responsive to said last movement for shifting said valve directly in response to said last movement, and means directly responsive to the movement of said valve for locking the movable member against further movement relative to the supporting structure during the remainder of the grinding operation.
7. In a grinding machine, a wheel supporting member having a wheel thereon, a work-supporting member having a workpiece mounted therein, hydraulically actuated means for procuring a relative movement between said members, means responsive to engagement between the wheel and the workpiece in the work-supporting member for procuring a movement of one of said members relative to the supporting structure therefor, and a valve movable directly in response to the movement of said movable member relative to the supporting structure for reducing the rate of relative movement between the members and for locking the movable member against further movement relative to the supporting structure.
8. In a grinding machine, a wheel supporting member having a wheel thereon, a work-supporting member having a workpiece mounted therein, hydraulically actuated means for procuring a relative movement between said members, means responsive to engagement between the wheel and the workpiece in the work-supporting member for procuring a movement of one of

said members relative to the supporting structure therefor, a valve movable directly in response to movement of said movable member relative to the supporting structure for reducing the rate of relative movement between the members, and means controlled by said valve for locking said movable member against further movement relative to the supporting structure.

9. In a grinding machine, a wheel supporting member having a wheel thereon, a work-supporting member having a workpiece mounted therein, a hydraulically actuated cross slide on which one of said members is mounted for a crossfeed movement between said members, means for supporting the wheel supporting member for a slight rocking movement relative to the supporting structure when the grinding wheel engages the workpiece in the work-supporting member, valve means responsive to said rocking movement for reducing the rate of crossfeed movement, and means responsive to said valve movement for locking the wheel supporting member against further rocking movement during the remainder of the grinding operation.

10. In a grinding machine, a wheel supporting member having a wheel thereon, a work-supporting member having a workpiece mounted therein, a hydraulically actuated cross slide on which one of said members is mounted for a crossfeed movement between said members, means for supporting the wheel supporting member for a slight rocking movement relative to the supporting structure when the grinding wheel engages the workpiece in the work-supporting member, and valve means directly responsive to said rocking movement for reducing the rate of crossfeed movement and for locking the wheel supporting member against further rocking movement.

HAROLD L. BLOOD. 40
